UNITED STATES PATENT OFFICE

132,563

DESIGN FOR AN ELECTRICAL FLOOR OUTLET BOX

Jacob W. Lewin, Chicago, Ill.

Application February 23, 1942, Serial No. 105,952

Term of patent 14 years

To all whom it may concern:

Be it known that I, Jacob W. Lewin, a citizen of the United States, residing at Chicago, in the county of Cook and State of Illinois, have invented a new, original, and ornamental Design for an Electrical Floor Outlet Box, of which the following is a specification, reference being had to the accompanying drawing, forming part thereof.

In the drawing:

Figure 1 is a front elevational view of an electrical floor outlet box embodying my design; and

Figure 2 is an end elevational view thereof.

The back side of the outlet box shown in Figure 1 is substantially the same as the front side, as indicated in the end elevational view of Figure 2.

I claim:

The ornamental design for an electrical floor outlet box, as shown and described.

JACOB W. LEWIN.
